STREET-SERVICE STRUCTURE

Hans Reichert, Berlin, Germany

Application April 7, 1937, Serial No. 135,578
In Germany April 9, 1936

1 Claim. (CL 189—2)

My invention relates to street-service structures, that is, to hollow structures erected on side walks, squares, etc., for the convenience of the public, in conformity with the requirements of 5 modern street traffic, and housing, or supporting, equipment such as a telephone, a fire alarm, in emergency calling apparatus, an elevator with a portable folded stretcher, a clock, a loud speaker, or any other equipment, as desired or required. 10 Such structures are usually of square cross-section, and have doors turning on hinges. The square cross-section is larger than required for the accommodation of a single person, and extra space must be provided for opening the door toward the inside, or the outside, of the structure. 15 The ground floor space occupied by the usual square structure is too large and often prohibitive, where space is limited.

It is an object of my invention to provide an 20 improved street-service structure which is without the drawbacks of the usual structure, requires minimum ground floor space, and has a door which does not give trouble.

To this end, I design the structure as a tubular 25 column, of circular cross-section, and equip it with a door mounted to slide on the column in turning about the axis of the column.

In the accompanying drawing, a street-service 30 column embodying my invention is illustrated more or less diagrammatically by way of example.

In the drawing

Fig. 1 is an elevation of the column.

Fig. 2 is a section on the line II—II in Fig. 1.

Fig. 3 is an axial section of the column's base, 35 showing the elevator, and

Fig. 4 illustrates a loud speaker on the column.

Referring now to the drawing, and first to Figs. 1 and 2, 1 is a parallel tube of circular 40 cross-section which will be referred to as the principal section of the column, and is of sheet metal, or any other suitable material. 22 is the base of the column which is also of circular cross-section but whose diameter is greater than that of principal section 1. The base is below the 45 street level SL. 23 is a narrow beveled annulus at the top of the base 22, for supporting the principal section 1. 10 is the roof of the column, shaped like an inverted dish, with a vertical flange 50 which is spaced from the principal section, and 11 are lamps on the underside of the inverted roof in the annular space between the flange and the principal section 1. Obviously, the roof must not project too far beyond the principal section 55 1, as this would spoil the appearance of the

column. In practice, for a column which is 16 feet high, the width of the annular space is about 7 in. The roof 10 supports a loud speaker 9 and a clock frame 8.

2 is a telephone cell in the lower portion of section 1, just above street level S, and the floor of the cell is the top plate 7' of an elevator 7 which is concealed in the base 22, as will be described. The cell 2 is equipped with a telephone 3, an emergency device 4 for calling the police or a rescue station, the fire brigade, etc., being arranged at one side of the telephone.

5 is the door of the cell. It is not hinged but is mounted to slide on the wall of section 1 in turning about the axis of the column. 24 is a 15 handle for pushing the door to the right when it is to be opened. Preferably, the frame of the door 5 is partly cut away and glass panes are inserted in the recesses. A window 6 is arranged opposite the door 5.

Under modern traffic conditions, structures of the kind described are practically indispensable but space conditions are often prohibitive. My column, on the other hand, is specially designed for restricted space, in that it is circular in cross-section and therefore smaller than the usual square section, and in that it has the sliding door which in all positions is flush with the wall of the section 1. A hinged door opens either inside, or outside, and in the first instance the 20 cell must be made comparatively large as otherwise the door cannot be closed from the inside. If the door opens outside this must be considered by distancing the structure from the nearest curb, or other object, for about the width of the door, 25 which is often impracticable. Apart from this the door while open is a great nuisance to passers-by. All these drawbacks are eliminated in my column whose sliding door 5 cannot give trouble as it does not project anywhere and therefore the 30 column can be placed quite near to curbs, houses, trees, and other objects which would prevent the operation of hinged doors.

My column is particularly suitable for supporting, or housing, certain accessories. As mentioned, an elevator 7 whose top plate 7' is normally the floor of the cell 2, is concealed in the base 22. Hydraulic means 12, Fig. 3, actuated by a motor-and-pump unit 13, control the elevator and, in turn, are controlled by switches, push buttons, levers, etc., in the cell 2. By these means, the elevator is raised into the cell 2, and lowered again, as desired. The elevator holds a folded portable stretcher 15, and a medicine chest 16, which are exposed by opening the sliding door 55

14. When the elevator is in its topmost position, the stretcher and the chest are removed through the opening of the door 5. The upward movement of the elevator is so limited that the 5 telephone and other equipment can still be used after the top plate 7' has moved to the upper end of its stroke. The door 5, being not hinged, is not in the way and the space in front of the column is unobstructed so that the stretcher is 10 easily handled.

15. The size of the elevator 7, and the arrangement of its operating means, should be so determined that the elevator is a self-contained unit, since it must move upwards into that portion of the 15 telephone cell 2 only which is not occupied by the equipment of the cell.

Preferably, the elevator 7 is of the platform type, that is, the members by which it is reciprocated, act as its guides at the same time, and the 20 space above the top plate 7' is not obstructed by extra guiding means. In other words, the elevator, in its topmost or active position, projects freely into the telephone cell 2.

Other accessories supported by the column are 25 the clock frame 8, and the loud speaker 17 which is placed on the roof 18 at the centre thereof. The loud speaker is preferably arranged as shown in Fig. 4, emitting sound in downward direction. In this case the sound is distributed uniformly to 30 all sides by the roof 18, which has at the same time the functions of a trumpet of a loud-speaker, in connection with the vanes 19, and the sound

gates 20, 21. The trumpet of the loud speaker extends therefore as far as the vertical flange of the roof 18. The means for operating the loud speaker are preferably arranged in the section 1 above the telephone cell 2.

This space can also be utilized for housing the 5 hydraulic means by which the elevator is operated, or part of such means, if there is no room for them in the base 22. Thus, the motor of the unit 13, or the complete unit, can be arranged 10 above the cell 2, and pipes and cables are preferably arranged between the inner wall of the section 1 and a suitable lining, or, better still, in the door or window frame. In this manner, crowding of the cell 2 is avoided.

The lamps 11 in the annulus between the 15 flange of the roof 18 and the section 1 project their light downward uniformly all over the outer surface of the column, as far as the street level, but the lighted zone is limited to the 20 column, and dazzling by stray light is avoided.

The cylindrical outer surfaces, and other parts 25 of the column, except the door 5 and the window 6, are available for sticking posters.

I claim:

In a street-service column which is of circular cross-section and defines an inlet opening, a roof plate at the upper end of the column, a loud speaker secured centrally to the roof plate, and sound-directing means partly constituted by the 30 roof plate.

HANS REICHERT.
